UNITED STATES PATENT OFFICE

140,912

DESIGN FOR A RADIATOR GRILL FOR MOTOR VEHICLES

Estol P. Korn, Houston, Tex.

Application September 11, 1944, Serial No. 115,259

Term of patent 3½ years

(Cl. D14—18)

To all whom it may concern:

Be it known that I, Estol P. Korn, a citizen of the United States, residing at Houston, in the county of Harris, in the State of Texas, have invented a new, original, and ornamental Design for a Radiator Grill for Motor Vehicles, of which the following is a specification, reference being had to the accompanying drawings, forming a part thereof.

Figure 1 shows a front elevational view of the radiator grill for motor vehicles showing my new design and

Figure 2 shows a side perspective view thereof.
I claim:

The ornamental design for a radiator grill for motor vehicles, as shown.

ESTOL P. KORN.
